(57) **CLAIM**

The ornamental design for a bin for automated pharmacy machine, as shown and described.

DESCRIPTION

FIG. 1 is a front perspective view of a bin for automated pharmacy machine showing our design;

FIG. 2 is a left side view of the bin for automated pharmacy machine of FIG. 1;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is a perspective view thereof showing the insertion of a "blister pack" pharmaceutical package into the bin.

The broken lines shown herein are for illustrative purposes only and form no part of the claimed design. The illustrated device is not limited to the scale shown.
